REAMER CUTTER MOUNTING MEANS

Alfred C. Catland, Alhambra, Calif., assignor to
Globe Oil Tools Company, Los Nietos, Calif., a
corporation of California

Original application November 18, 1938, Serial No.
241,205. Divided and this application March
10, 1939, Serial No. 260,973

8 Claims. (Cl. 255—73)

This invention relates to well drilling tools and relates more particularly to cutting means for rotary well reamers. A general object of this invention is to provide simple, practical and dependable means for rotatably supporting the cutters of rotary well reamers.

This application is a division of my co-pending application Serial No. 241,205, filed November 18, 1938.

10 Another object of this invention is to provide a well reamer structure in which the cutters and their anti-friction bearing means are in the nature of permanently assembled units convenient to handle and ship and easy to install.

15 Another object of this invention is to provide a reamer cutter assembly or unit embodying a novel anti-friction bearing means operable to transmit end thrusts or axial thrusts in both directions. It has been found in the actual operation of rotary well reamers that the cutters are often subjected to down thrusts as well as upward thrusts. The bearing means for typical rotary well reamer cutters embody anti-friction

20 bearings for the transmission of the upward thrusts on the cutters, but do not have anti-friction bearing means for taking the downward thrusts that may be imposed on the cutters. The cutter unit of the present invention embodies a novel dependable anti-friction bearing means adapted to assume both the upward and downward thrusts imposed on the cutters.

25 Another object of this invention is to provide a well reamer cutter and bearing assembly that cannot be disassembled or tampered with in any way after it has been correctly assembled at the place of manufacture.

30 Another object of this invention is to provide a cutter and bearing assembly of the character referred to that is simple and inexpensive to manufacture and that embodies a minimum number of simple, sturdy parts.

35 The various objects and features of my invention will be fully understood from the following detailed description of a typical preferred form 40 and application of the invention, throughout which description reference is made to the accompanying drawing, in which:

45 Fig. 1 is a fragmentary, vertical, detailed sectional view of a portion of a well reamer embodying the improved cutter assembly or unit of the invention and Figs. 2 and 3 are enlarged horizontal detailed sectional views taken as indicated by lines 2—2 and 3—3, respectively, on Fig. 1.

50 55 The present invention may be embodied in cut-

ter units for use on reamers, etc., varying considerably in construction and design and the cutter units may be secured to the well tools in any convenient or practical manner. In the drawing I have shown the invention embodied in a rotary cutter unit or assembly for a typical well reamer. While I have illustrated only one cutter assembly applied to the reamer it is to be understood that the reamer may embody a plurality of cutter units of like construction.

10 The portion of the reamer body 10 illustrated in Fig. 1 is provided at its periphery with a vertically extending recess 11 for receiving a cutter. The inner wall of the recess 11 may be concave while the upper and lower ends of the recess are preferably flat and horizontal. Radial or lateral sockets 12 are provided in the reamer body 10 above and below the recess 11. The sockets 12 connect with or join the recess 11 at the upper and lower walls of the recess.

15 The improved cutter assembly of the present invention may be said to comprise, generally, a rotatable cutter 13, a cutter supporting pin 14, and anti-friction bearing means 15 rotatably supporting the cutter 13 on the pin 14.

20 The cutter 13 is an elongate generally cylindrical member designed to rotate about its longitudinal axis. The lower portion of the cutter 13 may be tapered or frusto-conical. The periphery of the cutter 13 is provided with cutting means or cutting parts. These cutting parts may be in the nature of longitudinally extending teeth 16. The teeth 16 may be straight, axial teeth or may be spiraled. As illustrated in the drawing the teeth 16 may extend between the upper and lower ends of the cutter 13. The ends of the cutter 13 may be flat and horizontal. The upper outer corner of the cutter 13 may be bevelled off as at 17. In accordance with the invention a central longitudinal opening 18 extends through the cutter 13 from one end to the other. A bore or socket 19 of enlarged diameter is provided in the upper portion of the cutter 13 to join the opening 18. The socket 19 is cylindrical and is concentric with the cutter opening 18. The opening 18 is preferably cylindrical and uniform in diameter, as illustrated.

25 The pin 14 is an elongate rod or shaft for supporting the cutter 13 on the reamer body 10. The pin 14 extends longitudinally through the cutter opening 18 with suitable clearance and is of sufficient length to project beyond the upper and lower ends of the cutter for connection with the reamer body 10, as will be later described.

30 35 The anti-friction bearing means 15 supports

the cutter 13 on the pin 14 for free rotation. The means 15 includes a block or ring 20 secured in the socket 19 of the cutter 13. The ring 20 may closely fit the socket 19 and its lower end bears 5 on the bottom wall of the socket. The opening in the ring 20 passes the pin 14 with suitable working clearance. The upper end of the ring 20 is preferably flush with the upper end of the cutter 13. In the preferred construction the ring 10 20 is permanently and integrally connected with the cutter 13 so that it cannot be removed at the well or in the field. An annular weld 21 integrally joins the ring 20 with the cutter 13. The weld 21 is provided at the upper end of the ring 15 20. The upper outer corner of the ring 20 may be bevelled off to provide an annular space for receiving the weld 21.

The anti-friction bearing means 15 further includes bearing elements for transmitting axial 20 thrusts between the cutter 13 and the pin 14. An annular ball race 22 is provided in the pin 14 and is located to have its central horizontal axis either slightly below or slightly above the plane occupied by the bottom wall of the socket 19. 25 A ball race 23 is provided to surround and register with the race 22. The race 23 is partly formed in the lower inner corner of the ring 20 and partly formed in the cutter 13 where its opening 18 joins the socket 19. The arcs of curvature of the 30 ball races 22 and 23 are substantially 180° in extent so that the registering races provide an annular space that is cylindrical in cross section. A series of balls 24 occupies the registering races 22 and 23. The balls 24 cooperating with the 35 races 22 and 23 operate to transmit both the upward and the downward axial thrusts and, of course, assist in the transmission of the radial loads imposed on the cutter 13. It will be observed that the series of balls 24 is located in 40 the upper portion of the cutter 13 to support the upper part of the cutter for rotation.

The bearing means 15 further provides or includes vertically spaced annular grooves 25 in the pin 14. In the construction illustrated there are 45 two spaced grooves 25, one located substantially midway between the ends of the cutter 13 and one located in the lower portion of the cutter 13. The grooves 25 may be plain cylindrical grooves with flat upper and lower walls. Series of anti-friction rollers 26 occupy the grooves 25. The 50 rollers 26 are designed to engage the inner walls of the grooves 25 and to cooperate with the wall of the cutter opening 18 to transmit the radial thrusts from the cutter to the pin 14. It is to be understood that the cutter 13 may be entirely supported on the pin 14 by the balls 24 and the rollers 26. Accordingly, the cutter 13 may rotate with a minimum of friction during operation of the reamer.

60 The cutter assembly described above may be secured to the reamer body 10 in any selected or preferred manner. In the case illustrated the cutter assembly is secured to the reamer body 10 by attaching means of the character fully 65 described and claimed in my co-pending application referred to above. The attaching means includes blocks 27 applied to the projecting upper and lower portions of the cutter pin 14. The blocks 27 have vertical openings 28 receiving the 70 upper and lower parts of the pin 14. The blocks 27 are designed to occupy the sockets 12 in the reamer body 10. Horizontal openings 29 in the blocks 27 receive screws 30 which are threaded into sockets 31 in the body 10 to attach the blocks 27 to the body. The openings 29 inter-

sect or join the openings 28 and the opposite ends of the cutter supporting pin 14 have notches 32 for receiving the attaching screws 30. The heads 33 of the screws 30 are received in the openings 29 and the notches 32 and are provided 5 at their peripheries with knurling or teeth 34. Locking pins 35 are passed through horizontal openings in the blocks 27 and cooperate with the teeth 34 to prevent unthreading of the screws 30. The screws 30 in addition to attaching the blocks 10 27 to the body 10 cooperate with the notches 32 to hold the pin 14 against rotation and longitudinal shifting.

In assembling the cutter unit of the invention the rollers 26 are first inserted in their grooves 15 25 and are temporarily secured in the grooves by stiff grease, or the like. The pin 14 carrying the rollers 26 is then inserted in the opening 18 of the cutter 13 and is brought to a position where the race 22 substantially registers with the portion of the race 23 provided in the wall of the opening 18. The balls 24 are then entered through the socket 19 to their positions in the race 22 and the part of the race 23 in the cutter 13. When the balls 24 have been arranged in place the ring 20 is set in the groove 19 and is secured to the cutter 13 by the weld 21. When the weld 21 has been completed it may be ground off so that the cutter 13 and the ring 20 present a smooth, flat upper surface. The balls 24 co- 30 operating with the races 22 and 23 prevent vertical or longitudinal movement of the cutter 13 on the pin 14 and when the weld 21 has been formed the balls serve to prevent removal of the cutter from the pin 14. Accordingly the cutter 13 and its mounting or bearing means may be shipped and installed as a unit without further adjustment or manipulation. The assembly or unit may be correctly assembled at the place of manufacture with the assurance that the cutter 40 13 will be correctly and dependably supported when installed on the reamer. It will be apparent how the blocks 27 may be applied to the end portions of the pin 14 and then inserted in the sockets 12 for attachment in the body 10 by the 45 screws 30.

In the operation of the tool or reamer the cutter 13 projects from the body 10 and acts on the wall of the well to ream the same. This engagement of the cutter 13 with the well wall 50 causes rotation of the cutter 13 about its longitudinal axis. The series of balls 24 and the spaced series of rollers 26 dependably support the cutter 13 at longitudinally spaced zones for free rotation. The balls 24 cooperating with the races 55 22 and 23 are operable to transmit vertical thrusts in both directions making it unnecessary to employ thrust washers at the ends of the cutter 13. Accordingly, the ends of the cutter 13 may be clear or free of end supports, as illustrated in Fig. 60 1. The balls 24 also assist in the transmission of the radial thrusts. The spaced series of rollers 26 effectively transmit the heavy lateral or radial thrusts imposed on the cutter 13.

Having described only a typical preferred form 65 and application of my invention, I do not wish to be limited or restricted to the specific details herein set forth, but wish to reserve to myself any variations or modifications that may appear to those skilled in the art or fall within the 70 scope of the following claims:

Having described my invention, I claim:

1. In a well reamer, a reaming cutter having a longitudinal opening, a pin passing through said opening and projecting from the ends of the cut- 75

- ter, the pin having an annular ball race, one end portion of said opening being enlarged to form a socket, a ring inserted in said socket and integrally joined to the cutter, there being a ball race formed in said ring and the cutter at the inner wall of the socket to register with the first named race, and balls in the registering races rotatably supporting the cutter and transmitting end thrusts in both directions.
2. A reamer cutter assembly comprising a reamer cutter having a longitudinal opening, one end portion of the opening being enlarged to form a socket, a pin passing through the opening, the pin having an annular ball race, and spaced annular grooves, rollers in the grooves engaging the wall of said opening to assist in supporting the cutter on the pin, a ring arranged in the socket, there being an annular ball race formed in the ring and the adjacent part of the cutter to oppose the first named race, a weld securing the ring to the cutter, and balls in the said races transmitting end thrusts between the cutter and pin in both directions.
3. A reamer cutter assembly comprising a reamer cutter having a longitudinal opening, one end portion of the opening being enlarged to form a socket, a pin passing through the opening, the pin having an annular ball race, a ring in the socket, there being an annular ball race formed in the ring and the adjacent part of the cutter to oppose the first named race, balls in the races transmitting end thrusts between the cutter and pin in both directions, and welding securing the ring to the cutter.
4. A cutter assembly for a well tool comprising an elongate cutter having a longitudinal opening, an end portion of the opening being enlarged to form a socket, a pin passing through the opening and having an annular ball race, balls in said race, a ball race on the wall of the opening where it joins the socket cooperating with the balls for the transmission of end thrusts from the cutter to the pin in one direction, a member secured in the socket, and a ball race on the member cooperating with the balls for the transmission of end thrusts from the cutter to the pin in the other direction.
5. A cutter assembly for a well tool comprising an elongate cutter having a longitudinal opening, an end portion of the opening being enlarged to form a socket, a pin passing through the open-
- ing and having an annular ball race, bearing means spaced from said socket transmitting radial thrusts from the cutter to the pin, balls in said race, a ball race on the wall of the opening where it joins the socket cooperating with the 5 balls for the transmission of end thrusts from the cutter to the pin in one direction, a member secured in the socket, and a ball race on the member cooperating with the balls for the transmission of end thrusts from the cutter to the pin in 10 the other direction.
6. A cutter assembly for a well tool comprising an elongate cutter having a longitudinal opening, an end portion of the opening being enlarged to form a socket, a pin passing through the opening 15 and having an annular ball race, spaced sets of anti-friction elements engaged between the pin and the interior of the cutter at points spaced from the socket for transmitting thrusts from the cutter to the pin, balls in said race, a ball race 20 on the wall of the opening where it joins the socket cooperating with the balls for the transmission of end thrusts from the cutter to the pin in one direction, a member secured in the socket, and a ball race on the member cooperating with 25 the balls for the transmission of end thrusts from the cutter to the pin in the other direction.
7. A cutter assembly for a well tool comprising a roller cutter having a longitudinal opening and a socket in one end portion, a pin extending 30 through the opening and projecting from the cutter, roller bearing means in the other end portion of the cutter rotatably supporting the cutter on the pin, a ball race in the pin at the socket, 35 balls in the race, a race on the wall of the opening at the socket cooperating with the balls for the transmission of end thrusts in one direction, a member fixed in the socket, and a race on the member cooperating with the balls for the transmission of end thrusts in the other direction.
8. A cutter assembly for a well tool comprising a cutter having a longitudinal opening, a pin passing through the opening and having a ball race adjacent an end of the cutter, a series of balls in the race, a race on the wall of the opening cooperating with the balls for the transmission of end thrusts in one direction, a member attached to the cutter, and a race on the member cooperating with the balls for the transmission of end thrusts in the other direction.

ALFRED C. CATLAND.
